DESIGN FOR A WING NUT

Erwin L. Schmidt and Joseph L. Schwabe, Jr.,
Milwaukee, Wis., assignors to G-H Specialty
Co., Milwaukee, Wis., a corporation of Wisconsin

Application September 14, 1940, Serial No. 95,054

Term of patent 14 years

To all whom it may concern:

Be it known that we, Erwin L. Schmidt and Joseph L. Schwabe, Jr., citizens of the United States, residing at Milwaukee, county of Milwaukee and State of Wisconsin, have invented a new, original, and ornamental Design for a Wing Nut, of which the following is a specification, reference being had to the accompanying drawing, forming part thereof.

In the drawing:

Fig. 1 is a view in perspective of a wing nut embodying our new and ornamental design.

Fig. 2 is a view in side elevation of the wing nut shown in Fig. 1.

Fig. 3 is a view of the wing nut in plan.

Fig. 4 is a view of the wing nut in end elevation.

We claim:

The ornamental design for a wing nut, as shown.
